Specification for Design.

Patented Feb. 26, 1918.

Application filed November 15, 1917. Serial No. 202,246. Term of patent 7 years.

To all whom it may concern:

Be it known that I, KIERAN A. KELLY, a citizen of the United States, and a resident of the city of New York, borough of Manhattan, in the county and State of New York, have invented a new, original, and ornamental Design for a Banner, of which the following is a specification.

Reference is to be had to the accompanying drawing, in which—

Copies of this patent may be obtained for five cents each, by addressing the "Commissioner of Patents, Washington, D. C."

The figure is a face view of a banner formed in accordance with the present design.

I claim—

The ornamental design for a banner as shown.

KIERAN A. KELLY.
